CLAIM

The ornamental design for a patient support device with patient location indicators, as shown and described.

DESCRIPTION

FIG. 1 is a top plan view of one embodiment of a patient support device with patient locations indicators showing our new design;

FIG. 2 is a bottom plan view thereof;

FIG. 3 is a right side elevational view thereof;

FIG. 4 is a left side elevational view thereof;

FIG. 5 is a rear elevational view thereof; and,

FIG. 6 is a front elevational view thereof.

The broken lines of the handles and the pelvis in the drawings depict portions of the patient support device with patient indicator location indicators that form no part of the claimed design. The directional markings of the vertebral column and patient axis (X and Y axes) of FIG. 1 are intended to be claimed as patient location indicators.

1 Claim, 3 Drawing Sheets(56)
